(57) **CLAIM**

The ornamental design for a trap, as shown and described.

DESCRIPTION

FIG. 1 is a top, perspective view of a first embodiment of a trap;

FIG. 2 is a top plan view of the trap shown in FIG. 1;

FIG. 3 is a bottom plan view of the trap shown in FIG. 1;

FIG. 4 is a front elevational view of the trap shown in FIG. 1,

the rear elevational view being a mirror image thereof;

FIG. 5 is a left side elevational view of the trap shown in FIG.

1, the right side elevational view being a mirror image thereof;

and

FIG. 6 is an exploded perspective view of the trap shown in FIG. 1.

FIG. 7 is a top, perspective view of a second embodiment of a trap;

FIG. 8 is a top plan view of the trap shown in FIG. 7;

FIG. 9 is a bottom plan view of the trap shown in FIG. 7;

FIG. 10 is a front elevational view of the trap shown in FIG.

7, the rear elevational view being a mirror image thereof;

FIG. 11 is a left side elevational view of the trap shown in FIG.

7, the right side elevational view being a mirror image thereof;

and,

FIG. 12 is an exploded perspective view of the trap shown in FIG. 7.

The dashed broken lines shown in the figures illustrate portions of the trap that form no part of the claimed design. The dash-dot-dash broken lines shown in the figures define boundaries of the claimed design.

The claimed trap may be any color or combination of colors, and may have any surface finish or combination of finishes (gloss, matte, etc.).

1 Claim, 6 Drawing Sheets
